(57) **CLAIM**

The ornamental design for an electric fence, as shown and described.

DESCRIPTION

FIG. 1 is a front perspective view of a receiver, showing my new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is a front, bottom perspective view of a projector, showing my new design;

FIG. 10 is a rear, bottom perspective view thereof;

FIG. 11 is a front elevational view thereof;

FIG. 12 is a rear elevational view thereof;

FIG. 13 is a left-side elevational view thereof;

FIG. 14 is a right-side elevational view thereof;

FIG. 15 is a top plan view thereof;

FIG. 16 is a bottom plan view thereof;

FIG. 17 is a front perspective view of the electric fence consisting of a projector and a receiver, showing my new design; and,

FIG. 18 is a rear perspective view thereof.

The broken lines show portions of the the electric fence, that form no part of the claimed design.
